CLAIM

The ornamental design for a touch pad terminal, as shown and described.

DESCRIPTION

FIG. 1 is an elevated perspective view of the touch pad terminal in accordance with the invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The phantom lines, shown in FIGS. 1 and 2, represent a configuration of a display screen and are shown for illustrative purposes only forming no part of the claimed design.
